UNITED STATES PATENT OFFICE.

LINDLEY KLEINHANS, OF PITTSBURGH, PENNSYLVANIA.

RAILWAY DUMP CAR.

Application filed July 27, 1925. Serial No. 46,440.

To all whom it may concern:

Be it known that I, LINDLEY KLEINHANS, a citizen of the United States, residing at Pittsburgh, in the county of Allegheny and 5 State of Pennsylvania, have invented a new and useful Improvement in a Railway Dump Car, of which the following is a specification.

This invention relates to a dumping car 10 construction.

The general object of the invention is to provide a construction in conjunction with a dump car whereby the door on either side of the car which is tilted downwardly into 15 discharging position is automatically extended, and is held in extended position to form a delivery chute for the material in the car.

Another object of the invention is to provide 20 door supporting means of the character indicated which act wholly by gravity, so that the shifting of centers due to tilting of the car body serves to open and extend the door on the discharge side of the car.

Another object of the invention is to provide 25 a safety lock for preventing undesired opening of the car door on the side of the body which is raised during the dumping operation.

Still further objects of the invention are to provide readily disengageable connecting 30 means which are applicable to use in the mechanism of the present invention, and a door hinge which is so arranged that the doors may be readily lifted from position on the floor of the car body.

In the accompanying drawings Figure 1 is an end elevation of a dumping car, showing the mechanism of the present invention; 40 Figure 2 is a side elevation of one end of the car showing the door operating mechanism for the end shown; Figure 3 is an end elevation similar to Figure 1, but showing in full lines the car body and the door operating mechanism in an intermediate position assumed during the swinging of the car body to dumping position, and showing in dotted lines the car body and the door on the dumping side thereof in fully swung or 45

dumping position; Figure 4 is a fragmentary sectional view through the car body, showing in elevation the hinge for securing a door to the floor of the body and the stop member associated with the door; 55 Figure 5 is a front elevation of the upper

leaf of the hinge; Figure 6 is a detail end elevation of the means for engaging the operating arms on one side of the car for locking the car body in carrying position and for locking the door operating mechanism; Figure 7 is a vertical sectional view of the same, taken on the line 7—7 Figure 6; Figure 8 is a detail side elevation of the pivoting means for the operating arms which provide pivotal points and connections for the operation of the car door; and Figure 9 is a front elevation of the members shown in Figure 8. In the drawings the reference numeral 1 indicates generally the under frame of a dumping car to which the mechanism of the present invention is applied. Reference numeral 2 designates a pedestal mounted on the draft beam 3 of the car. On this pedestal 2 is a pivot pin 4 for connection with the supporting lug or block 5 on the under side of the car body 6. Two or more such pivotal connections may be provided for the car body.

Means for locking the car body in carrying position, and for engaging the door operating arms of the car, comprise brackets 7 and 7^a disposed one on each side of the car, and having respectively upwardly extending pedestal arms 8 and 8^a. The pedestal arm 8 is provided with an aperture 9 arranged 60 to receive a pin 10 on an arm 11. This arm 11 is pivotally mounted on a pin 16 extending through yoke 12, which is hinged at 13 to the arm 11 so that the entire member may be broken part way of its length.

As shown in Figure 7 of the drawings, the pedestal arm 8 and arm 11 are held in mutual engagement by means of the pin 10 passing through the aperture 9 in the pedestal arm 8. Withdrawal of the pin 10 from its engaging aperture is prevented by means of a squared sleeve 14 which slides down over the engaging extremity of the arm 11 and a lug 15 on the pedestal arm 8. To disengage these arms the sleeve 14 is forced 70 upwardly and the pin 10 forced out of engagement with the aperture 9, this action being permitted by the hinged construction of the arm 11.

Similarly the pedestal arm 8^a on the other side of the car is provided with an aperture 9^a for the engagement of a pin 10^a carried by the arm 11^a, the upper extremity of which provides the pivotal pin 12^a, and which is similarly hinged at 13^a. This con- 80

struction being identical with that on the other side of the car, is likewise provided with the sleeve 14^a slidable on the arm 11^a and engaging a lug 15^a on the pedestal arm 8^a, which cooperates with the lower portion of the arm 11^a.

The pivot pins 16 and 16^a, mounted in the yoke or pivotal members 12 and 12^a of the arms 11 and 11^a carry respectively arms 17 and 18 and arms 17^a and 18^a. The arms 18 and 18^a are both pivoted on a pin 19 in a strap or bar 20, which extends downwardly beyond the car body 6. The pivot pin 19 is in direct alignment with the pivotal connections 4 for the car body. Stop bars 21 and 21^a, secured to the end of the car body, have hooked portions 22 and 22^a engaging respectively the under sides of the arms 18 and 18^a.

20 The car doors 23 and 23^a are pivotally secured to the car body 6 by means of hinges indicated generally by the reference numerals 24 and 24^a for the different doors. Each of these hinges comprises a leaf 25, secured to the floor 26 of the car body, and provided with an open ferrule or channel 27. The other leaf 28 is provided with a hinge pin 29 lying in the channel 27. The doors 23 and 23^a are provided respectively with the stop bars 30 and 30^a which extend downwardly beyond the floor 26 of the car body 6.

35 Arms 17 and 17^a are pivotally connected by pins 31 and 31^a with arms or bars 32 and 32^a, which are secured respectively to the doors 23 and 23^a.

40 Arcuate straps 33 and 33^a may be desirably provided to serve as additional means for limiting the outward swinging of doors 23 and 23^a. These straps are secured to the doors adjacent the upper extremities of the latter, and have thereon stop lugs 34 and 34^a. Staples 35 and 35^a overlie the straps 33 and 33^a, and serve as limiting means for the lugs 34 and 34^a.

45 It should be understood that the structure described above is duplicated in identical form for both ends of the car. Since the form and arrangement of the parts is identical for both ends, the description of the device as applied to one end should be sufficient.

50 In Figure 1 of the drawings, the car, and the mechanism of the present invention associated therewith, is shown in level or carrying position. In order to bring the car body and one of the doors of the car into the dumping position shown in Figure 3, one of the arms 11 or 11^a is first disengaged from its corresponding pedestal arm 8 or 8^a. As shown in Figure 3, the arm 11^a to the right of the drawing is disengaged to permit dumping of the car on the side to the left in the drawing.

65 Disengagement of the pedestal arm 11^a

is effected by forcing sleeve 14^a upwardly from engagement with the lug 15^a. The effective length of the arm 11^a may then be decreased by forcing its parts outwardly at their point of pivotal connection 13^a. This permits withdrawal of pin 10^a from the orifice 9^a in the bracket or pedestal arm 8^a. The jointed structure of the arms 11 and 11^a is rendered necessary by the fact that the pivot pins 16 and 16^a, on which they are mounted, are fixed points in the mechanism.

When arm 11^a has been freed, tilting movement of the car body 6 may be started by applying any lifting force to that side 80 of the body at which the pedestal arm has been disengaged, by shifting the material toward the other side of the body, or by an unequal loading of the car.

During this tilting movement the door on the high side of the car is maintained in closed position by the action of stop bar 21^a on the transverse arm 18^a, this stop bar preventing downward rotation of the arm 18^a about the pin 19 as a center. In this connection it should be noted that the pivot pin 16^a to which both the transverse arm 18^a and the door operating arm 17^a are connected is disposed at a point below a straight line drawn between the pivot pin 19 and the pivot pin 31^a which connects the door operating arm 17^a with the bar 32^a secured to the door 23^a. Because of this positioning the resultant of the forces tending to swing the door to open position is directed downwardly against the engaging lug 22^a of the stop bar 21^a, and movement of the parts for operating the door is thus positively prevented. On the downward swinging side of the car body, the change of position of the pivotal center 31 with respect to the pivotal center 16 causes the arm 17 to swing inwardly on its pivot 16. The transverse arm 18 is rigid between its pivotal points 16 and 19. As the door operating arm 17 swings downwardly and inwardly, the door 23 swings around the pivotal connection 29 between arm 17 and bar 32 until it assumes a position in line with the floor 26 of the car body, as shown in dotted lines in Figure 3 of the drawings. It is prevented from swinging below the floor line by the engagement of stop bar 30 with the under side of the floor 26. If the arcuate stops 33 and 33^a are likewise provided, further swinging movement is also prevented by the engagement of the stop lug 34 on bar 33 with staple 35 on the car body.

It will be understood that the same action occurs at both ends of the car.

As the car body is restored to horizontal or carrying position door operating arm 17 swings upwardly and outwardly about the pivot pin 16 to restore the door to its closed position. When the car body has been re-

90

115

120

125

130

stored to horizontal or carrying position the arms 11^a at both ends of the car are reconnected to their bracket or pedestal arms 8^a. This is effected by bringing the locking pin 10^a on each arm into the orifice 9^a of its pedestal arm. The sleeve 14^a is then forced downwardly over the lug 15^a to secure the arm in position. It should be noted that the device described above is simple in construction and automatic in operation. It should be further noted that the arrangement is such as to prevent undesired opening on either door with the car body in horizontal or carrying position, and to prevent undesired opening of the door on the high side of the car body during tilting movement of the body.

The stop bars 21 and 21^a not only prevent undesired opening of the door on the high side of the car body during dumping but the lug on the stop bar on the side which has been dumped tends to absorb the shock when the parts on this side of the car assume their normal or carrying position.

25 What I claim is:

1. In dumping car construction the combination of a car underframe, a tiltably mounted body, members extending upwardly from the underframe on both sides of the car, and arms pivotally mounted on the longitudinal center line of the car body and on said members for normally preventing tilting movement of the body.

2. In dumping car construction the combination of a car underframe, a tiltably mounted body, members extending upwardly from the underframe on both sides of the car, and arms pivotally mounted on the longitudinal center line of the car body and on said members for normally preventing tilting movement of the body, and stop members secured to the car body and engaging said arms.

3. In dumping car construction the combination of a car underframe, a tiltably mounted body, members extending upwardly from the underframe on both sides of the car, and arms pivotally mounted on the longitudinal center line of the car body and on said members for normally preventing tilting movement of the body, said upwardly extending members being arranged for disengagement from the underframe at either side of the car to permit tilting movement of the car body.

4. In dumping car construction the combination of a car underframe, a tiltably mounted body, members extending upwardly from the underframe on both sides of the car, arms pivotally mounted on the longitudinal center line of the car body and on said members for normally preventing tilting movement of the body, and stop members secured to the car body and engaging said arms, said upwardly extending mem-

bers being arranged for disengagement from the underframe at either side of the car to permit tilting movement of the car body.

5. In dumping car construction the combination of a car underframe, a tiltably mounted body, members extending upwardly from the underframe on both sides of the car, arms pivotally mounted on said members and at a point disposed transversely of the car with respect thereto for normally preventing tilting movement of the car body, hinged doors on the car body, and arms pivotally connected with the upwardly extending members and with the doors arranged to normally prevent outward swinging of the doors but to permit outward swinging of the door on the low side of the car body during tilting movement thereof.

6. In dumping car construction the combination of a car underframe, a tiltably mounted body, members extending upwardly from the underframe on both sides of the car, arms pivotally mounted on said members and at points disposed transversely of the car with respect thereto for normally preventing tilting movement of the body, stop members secured to the car body and engaging said arms, hinged doors on the car body, and arms pivotally connected with the upwardly extending members and with the doors arranged to normally prevent outward swinging of the doors but to permit outward swinging of the door on the low side of the car body during tilting movement thereof.

7. In dumping car construction the combination of a car underframe, a tiltably mounted body, members extending upwardly from the underframe on both sides of the car, arms pivotally mounted on said members and at a point disposed transversely of the car with respect thereto for normally preventing tilting movement of the body, said upwardly extending members being arranged for disengagement from the underframe at either side of the car to permit tilting movement of the car body, hinged doors on the car body, and arms pivotally connected with the upwardly extending members and with the doors arranged to normally prevent outward swinging of the doors but to permit swinging movement of the door on the low side of the car body during tilting movement thereof.

8. In dumping car construction the combination of a car underframe, a tiltably mounted body, members extending upwardly from the underframe on both sides of the car, arms pivotally mounted on said members and at a point disposed transversely of the car with respect thereto for normally preventing tilting movement of the body, stop members secured to the body and engaging said arms, said upwardly extending

members being arranged for disengagement from the underframe at either side of the car to permit tilting movement of the car body, hinged doors on the car body, and 5 arms pivotally connected with the upwardly extending members and with the doors arranged to normally prevent outward swinging of the doors but to permit outward swinging of the door on the low side of the 10 body during tilting movement thereof.

9. In dumping car construction the combination of a car underframe, a tiltably mounted body, members extending upwardly from the underframe on both sides of the 15 car, arms pivotally mounted on said members and at a point disposed transversely of the car with respect thereto for normally preventing tilting movement of the car body, hinged doors on the car body, arms 20 pivotally connected with the upwardly extending members and with the doors arranged to normally prevent outward swinging of the doors but to permit outward swinging of the door on the low side of the 25 car body during tilting movement thereof, and stop members on the doors arranged to prevent swinging movement of the free door beyond the floor line of the car body in tilted position of the body.

30 10. In dumping car construction the combination of a car underframe, a tiltably mounted body, members extending upwardly from the underframe on both sides of the car, arms pivotally mounted on said members and at a point disposed transversely of the car with respect thereto for normally preventing tilting movement of the body, stop members secured to the car body and engaging said arms, hinged doors on the car 35 body, arms pivotally connected with the upwardly extending members and with the doors arranged to normally prevent outward swinging of the doors but to permit outward swinging of the door on the low side of the 40 car body during tilting movement thereof, and stop members on the doors arranged to prevent swinging movement of the free door beyond the floor line of the car body in tilted position of the body.

45 11. In dumping car construction the combination of a car underframe, a tiltably mounted body, a member extending upwardly from the underframe, an arm pivotally mounted on said member and at a point disposed transversely of the car body with 50 respect thereto, a hinged door on the car body, and a door operating arm pivotally connected with said door and with said upwardly extending member, the arrangement being such that the pivotal point of the upwardly extending member lies below a line drawn from the pivotal connection of the door and door operating arm to the outer 55 pivotal point of the transverse arm, and a 60 stop member secured to the door body and

engaging the lower side of the transverse arm.

12. In a dumping car construction the combination of a car underframe, a tiltably mounted body, a member extending upwardly from the underframe and disengageable therefrom, an arm pivotally mounted on the pedestal arm and at a point disposed transversely of the car body with respect thereto, a hinged door on the car body, and a door 75 operating arm pivotally connected with said door and with the upwardly extending member, the arrangement being such that the pivotal point of the pedestal arm lies below a line drawn from the pivotal connection of the door and door operating arm to the outer pivotal point of the transverse arm, and a stop member secured to the car body and engaging the lower side of the transverse arm. 80

13. As a mechanical element the combination of a bracket arm having an orifice therein, an arm hinged intermediate its length and carrying a pin arranged to engage in said orifice, a lug on said bracket arm, and a sleeve arranged to engage both said lug and said jointed arm for preventing withdrawal of the pin from the orifice. 85

14. As a mechanical element the combination of a bracket member having an orifice therein, an arm carrying a pin arranged to engage in said orifice, a lug on said bracket member, and a sleeve arranged to engage both said lug and said arm for preventing the withdrawal of the pin from the orifice. 90

15. In dumping car construction the combination of a car underframe, a tiltably mounted body, a member on the underframe having an orifice therein, an upwardly extending arm hinged intermediate its length and carrying a pin arranged to engage in said orifice, a lug on said member, means arranged to engage both said lug and said arm for preventing withdrawal of the pin from the orifice, a hinged door on the car body, and an arm pivotally connected to said member and arranged to normally prevent outward swinging of the door but to permit outward swinging thereof during tilting movement of the car body toward the side on which such door is mounted. 100

16. In dumping car construction the combination of a car underframe, a tiltably mounted body, members on the underframe and having orifices therein, an upwardly extending arm hinged intermediate its length associated with each member, lugs on said members, means arranged to engage said arms and the lugs of said members for preventing withdrawal of the pins from the orifices, and arms pivotally mounted on the longitudinal center line of the car body and on said members for normally preventing tilting movement of the body. 110

17. In dumping car construction the combination of a car underframe, a tiltably 120

mounted body, upwardly extending members on the underframe and having orifices therein, an upwardly extending arm hinged intermediate its length associated with each 5 upwardly extending member, lugs on said members, means arranged to engage said arms and the lugs of said members for preventing withdrawal of the pins from the orifices, arms pivotally mounted at the longitudinal center line of the car body and on 10 said upwardly extending members for normally preventing tilting movement of the car body, and arms pivotally connected with the upwardly extending members and with the doors arranged to normally prevent outward swinging of the doors but to permit outward swinging of the door on the low side of the car body during tilting movement thereof. 15

In witness whereof, I hereunto set my 20 hand.

LINDLEY KLEINHANS.
